UNITED STATES PATENT OFFICE.

WARREN HERBERT FROST, OF CLEVELAND, OHIO.

GARMENT-CLASP.

SPECIFICATION forming part of Letters Patent No. 309,615, dated December 23, 1884.

Application filed October 28, 1884. (No model.)

To all whom it may concern:

Be it known that I, WARREN HERBERT FROST, a citizen of the United States, residing at Cleveland, in the county of Cuyahoga and State of Ohio, have invented a new and useful Garment-Clasp, of which the following is a specification.

My invention relates to improvements in garment-clasps; and the objects of my improvements are, first, to provide a garment-clasp which will hold the garment firmly when attached thereto without perceptably wearing or tearing said garment; second, to provide a garment-clasp that can be quickly and easily fastened to the garment; third, to provide a garment-clasp that can be cheaply made and be strong and durable. I attain these objects by means illustrated in the accompanying drawings, in which—

Figure 1 is a front view of the entire clasp. Fig. 2 is a side view of the clasp, showing a bunch of garment clamped therein. Fig. 3 is a front view of a part of the clasp, showing garment securely clamped. Fig. 4 represents a part of piece A, showing the edge E.

Similar letters refer to similar parts throughout the several views.

The piece A is preferably stamped from sheet metal, (though it could be made of wire,) having large hole C, (shown by dotted lines in Fig. 1,) and with the lower end, G, bent at an angle to the main part. For convenience in attaching to web or tape, I can make the slit H. Small ears J' and J are bent at right angles to the main part. The piece B is also preferably stamped from sheet metal, (though it could be made of wire,) and is provided with projections K' and K and with notches F' and F. Small ears L' and L are bent at right angles to the main piece. Through the ears J' and J and L' and L, I pass a pin or rivet, M. The piece B is now pivoted to the piece A by the rivet M, and can be swung out, as shown by dotted lines O in Fig. 2.

Although I prefer this construction and the

use of sheet metal, the clasp can be made in whole or part of wire, and the construction as described slightly altered, while the principle of clamping or holding the garment would remain the same, substantially as described. 50

The manner of operation is as follows: The swinging part B being raised, the garment is caught between the thumb and forefinger and a bunch of the same drawn through the hole C in the piece A. The swinging part B is now pushed down, clamping the garment between the lower edges, D and E, and the turned-up end G, as shown in Fig. 2. The clasp could thus be made and used without having notches F' and F; but, to insure a still 60 tighter clamp, the bunch of garment is passed over the end of the piece B until it catches in the notches F' and F. The garment is thus securely held, and if the garment is pulled or strained the contact between the lower edges 65 of the pieces A and B is made closer, bringing a tighter clamp on the bunch of garment between them.

I am aware that many forms of garment-clasps have been and are made; but 70

What I claim, and desire to have protected by Letters Patent of the United States, is—

1. In a garment-clasp, the combination of the piece A, made of metal, having a hole, C, with a piece, B, hinged thereto, having notches 75 F and F', and with its lower edge, D, projecting slightly beyond the edge E.

2. The combination of the piece A, having hole C, and turned up at its lower edge G, with the piece B, hinged thereto, B having notches 80 F and F', and its lower edge, D, projecting slightly beyond the edge E, as set forth.

3. The combination of the piece A, having hole C, and turned up at its lower end, G, with a piece hinged thereto, its lower edge projecting slightly beyond the edge E. 85

WARREN HERBERT FROST.
